OF ONE-HALF TO PACKAGE MACHINERY COMPANY, A CORPORATION OF MASSA-
CHUSETTS.

PAPER-FEEDING APPARATUS.

1,092,437

Specification of Letters Patent.

Patented Apr. 7, 1914.

Application filed October 21, 1909. Serial No. 523,826.

To all whom it may concern:

Be it known that I, MILFORD B. FERGUSON, a citizen of the United States, residing at New York, in the county of Kings and State of New York, have invented certain new and useful Improvements in Paper-Feeding Apparatus, of which the following is a full, clear, and exact description.

This invention relates to paper-feeding mechanism, for feeding sheets of paper singly from a stack and delivering the same to a wrapping machine, printing press, or other apparatus in which the paper is to be utilized.

Supplying paper by feeding the same from a roll and severing measured lengths therefrom at the proper intervals of time is comparatively simple, but feeding single sheets from a stack is a problem of a very different order, the chief difficulty encountered being the liability of the mechanism to occasionally to feed off two or three sheets instead of always one sheet at a time.

The primary object of my present invention is to provide an apparatus which will feed off single sheets with the utmost certainty and that without tearing or creasing the paper in the operation.

A further object is to simplify the apparatus as much as possible and to make the operation such as will prevent the deterioration of the feeding devices, thereby keeping the latter at all times in the best operative condition and insuring the desired certainty of operation.

In general, my invention comprises a series of frictional feeding wheels or disks which at regular intervals are raised against the bottom sheet of the stack. These feeding disks are driven by a mechanism constructed to give them a varying speed of rotation, and the operation of the devices which effect the elevating of the disks against the pile of sheets is so timed that at the instant of initial contact with the undermost sheet the disks are revolving at minimum velocity; this mode of operation insuring good frictional engagement with the sheet so that the same will immediately begin to move from off the stack. As the paper travels forward the speed of the feeding disks is accelerated, thereby increasing the speed of the paper, and immediately after the sheet is freed from the stack the

disks are lowered out of operative engagement therewith, after which their speed is decreased to the minimum.

It will be apparent to those skilled in the art that the scheme thus briefly outlined can be embodied in various forms of apparatus, and of these embodiments I have selected for specific description herein the form which at the present time is considered to exhibit the best mode of applying the invention in practice. This form of the invention is illustrated in the annexed drawings, and referring now thereto,

Figure 1 shows the complete apparatus in side elevation. Fig. 2 is a top plan view of the same. Fig. 3 is a section on line III—III of Fig. 1. Fig. 4 is a detail sectional view of the mechanism for driving the feeding disks with varying speed, the section being taken substantially on line IV—IV of Fig. 1. Figs. 5 and 6 are side views, diagrammatic in character, showing different positions of the feeding devices and the variable speed mechanism.

The stack of paper sheets rests on a bed frame composed of longitudinal members 1 and transverse cylindrical rods 2, and is confined at the sides by vertical side-plates 3 and at the front by vertical front plates 4. At the rear each side-plate is supported by an angle piece 5 which is adjustably mounted on the transverse member 6, of the frame of the apparatus, said side-plates being thus adjustable to vary the distance between them so as to accommodate sheets of different sizes. At the front each side-plate is connected to the adjacent front plate by a connecting member 7 bolted to an angle piece 8 on the front-plate. The front-plates themselves are fixed to a supporting rail or bar 9, extending across the machine and supported at the sides of the machine by adjusting screws 10. The front-plates are thus capable of vertical adjustment so as to be accurately located in such position as to permit the passage of the paper under them and yet confine the stack to its proper place on the bed-frame; said vertical adjustment being permitted by the bolt connection of the plates with the members 7 and by the slot-and-bolt connection 11 of the latter with the side plates, as will be readily understood.

Below the bed-frame and registering with the spaces between the transverse sup-

porting rods 2 are four feeding shafts 12, 13, 14, 15, having driving gears 16, 17, 18, 19 respectively, meshing with connecting gears 20, 21, 22. On the first feeding shaft, 5 12, is a gear 23 meshing with a main driving gear 24 on the driving shaft 25, from which the entire train is actuated. The shafts 12, 13, 14, 15 are journaled in side frames 26, which are capable of vertical 10 reciprocation on the guide rods 27, 28. The feeding shafts carry feeding disks 29, faced with soft rubber or other suitable material affording good frictional engagement with the paper, and it will be seen that as the 15 supporting frames 26 are raised and lowered the feeding disks will be brought into and out of contact with the undermost sheet of the stack. This raising and lowering of the frames is effected by means of 20 suitable cams 29^a on the spindles which carry the connecting gears 20 and 22, and by similar cams, not shown, at the opposite side of the machine, driven by similar gears 30, 31, meshing with driving gears 32, 33, 25 on the shafts 13 and 15 respectively. The cams themselves bear on anti-friction rollers 34.

From the foregoing it will be seen that during a part of each rotation of the gears 30 20, 22, 30, 31, and feeding disks 29, the feeding disks are raised into contact with the paper and during the remaining portion are lowered out of contact therewith. Since the feeding disks engage the paper 35 during only a part of this revolution the wear on the disk-facings would be uneven if the engagement were always on the same portion of the facings and the latter would therefore suffer rapid deterioration. This 40 result is avoided, however, by so proportioning the actuating gears that the disks will make more or less than a complete revolution in each cycle of movement of the supporting side frames by which the disks 45 are brought into engagement with the paper, the result being that each engagement begins on a fresh portion of the disk-facings, as will be readily understood. In the present embodiment this object is accomplished 50 (except in the case of the first feeding gears, on shaft 12,) by giving the connecting gears 20, 21, 22, each one less tooth than the driving gears, 17, 18, 19, the result being that the shafts 13, 14, 15, and hence the feeding 55 disks carried thereby, rotate at lower speed than do the connecting gears, which latter it will be remembered, effect the vertical movements of the side frames and feeding disks through the instrumentality of the 60 cams 29^a. The gear 23, however, which rotates shaft 12 and the feeding disks thereon, has a ratio of unity to the driving gear 24, so that this shaft and its feeding disks 65 rotate at the same rate as the driving shaft 25; while the gear 16, rotating at the same

rate, has the same ratio (unity) to the connecting gear 20, thereby causing the connecting gears to revolve at the same rate as the driving shaft 25, and the driving gears 17, 18, 19 to revolve at a slower rate. It will therefore be seen that by reason of the differential gearing described the feeding disks on shafts 13, 14, 15 will make slightly less than a whole revolution at each cycle of movement of the supporting frames 26, and hence the contact with the paper will always begin at a different point on the disk facings. It will be remembered, however, that the shaft 12 and its feeding disks revolve at the same rate as the driving shaft 25; that is, faster than the disks on the other feeding shafts. This difference of operation insures that the portion of the paper sheet between the first and second series of disks will always be taut, since the tendency is to pull the forward part of such portion faster than the rear part; tearing being prevented by the fact that the forward disks can take only a comparatively light grip on the sheet, and hence will slip on the paper. 90

As previously stated, the feeding disks revolve at varying speed, their rotation being slowest at the beginning of their engagement with the paper and fastest as they are carried down and out of engagement. 95 This operation is effected preferably by the mechanism now to be described, attention being directed to Fig. 4.

On the end of the driving shaft 25 is a crank arm 36 having a crank pin 37 extending into a slot 38, in the adjacent face of an arm 39 fixed on the end of a power-driven shaft 40. The axis of the latter shaft is parallel to the axes of shaft 25 and pin 37, but is so located as to lie between the two when all three are in the same plane, and the pin 37 is in its nearest position to shaft 40, as in Fig. 4. The rotation of the shaft 40 will of course impart rotary movement to the shaft 25 through the instrumentality of the crank 36. Assuming the parts to be in the position of Fig. 4, it will be seen that as the arm 39 revolves its point of engagement with the crank pin 37 will shift radially outward, as in Fig. 5, 115 causing the crank 37 to revolve at a correspondingly increasing speed, until the arm 39 has turned half a revolution; at which time the pin 37 is at its maximum distance from the shaft 40 and hence is moving at maximum speed. From this point the speed of the crank diminishes, since the pin is approaching the shaft 40 as in Fig. 6, until the position of Fig. 4 is again reached, when the speed of the crank is at its minimum. 125 The power driven shaft 40 is stationarily mounted and as the shaft 25 is journaled in the movable frame it will be obvious that there will be a movement of the axis of the driving shaft relative to the axis of the 130

power shaft in the operation of the machine. As shown in Fig. 1, the pin 37 is nearest the shaft 40 when the crank 36 is at its lowest position; hence the cams 29^a are so designed and arranged that at this position of the crank the frames 26 will bring the feeding disks into contact with the paper. The speed of the driving shaft is now increasing and hence the disks revolve with increasing speed, up to the maximum, at which points the cams allow the frames to descend and carry the disks out of engagement with the paper. At this time, however, the sheet reaches the coöperating conveying belts 41, 42, and, being seized between the same, is carried swiftly away to the point of utilization. The lower belts run over two pulleys 43 (only one of which is shown) fixed to a shaft 44, the latter being driven by a pinion 45 in mesh with a gear 46 on the power shaft 40. The upper belts run over idle pulleys 47 mounted on a shaft 48 which is capable of vertical movement in its bearings 49. Connected to the ends of this shaft are two downwardly acting springs 50, serving to give the upper belts a strong downward pressure and thus insure a firm engagement of the upper and lower belts or conveyors with the paper sheet.

Under the rear end of the stack of sheets is a bar 51, adjustable toward the front and rear, according to the size of the paper sheets, carrying needles or slender knives 52 which pierce the bottom sheet or sheets near the rear edge thereof. As the bottom sheet is fed forward it is slit or torn by the needles; but the friction of the bottom sheet on the second is not sufficient to overcome both the resistance of this second sheet to being torn by the needles, and its friction on the third sheet, and hence only the bottom sheet will be moved forward by the feeding disks. The needles are preferably inclined rearwardly, as shown in Fig. 1, as in this position they tend to separate the bottom sheet from the one next above. This is due to the fact that as the bottom sheet starts it slides down toward the base of the needles, thereby pulling itself away from the adjacent sheet. At the same time the downwardly moving sheet forces down and away from the points of the needles any portions of paper that may tend to accumulate, thereby keeping the points free and clear.

The operation of the machine having been described in connection with the mechanism further description of the operation is deemed unnecessary. Suffice it to say that extensive practical use of the apparatus has demonstrated its effectiveness, the paper being fed one sheet at a time with certainty and precision. At this point it may be stated that in using the machine with sheets of paper so short that before the feeding

disks are lowered the next sheet above the bottom will be exposed to and therefore be engaged by the last series of disks the latter may be made idle by omitting the last driving gear, 19.

It is to be understood, of course, that the invention is not limited to the precise construction herein shown and described, but is capable of embodiment in various forms without departure from its proper spirit and scope as defined by the appended claims.

What I claim is:

1. In a paper-feeding apparatus, in combination, a support for a stack of paper sheets, feeding disks below the support, means for raising and lowering the disks to carry the same into contact with the paper a given number of times in a given period of time, and driving mechanism for the feeding disks, constructed to rotate the disks a different number of times in the same period, whereby each contact with the paper will begin at a different point on the disks.

2. In an apparatus for feeding paper, in combination, a support for a stack of paper sheets, feeding disks below the support, means for raising and lowering the disks to carry the same into and out of contact with the paper at a given rate, means for rotating the disks at a different rate, and means giving the disks a minimum speed of rotation at the beginning of each contact and increasing to a maximum at the end of each contact.

3. In a paper-feeding apparatus, in combination, a support for a stack of paper sheets, feeding disks below the support, means for raising and lowering the disks to carry the same into and out of contact with the paper, mechanism for rotating the disks, and one or more upwardly extending rearwardly inclined needles arranged to engage the bottom of the stack at the rear thereof.

4. In a paper-feeding apparatus, in combination, a support for a stack of paper sheets, a pair of vertically movable side-frames below the support, a driving shaft and transverse feeding shafts journaled in the side-frames the latter carrying feeding disks, gearing arranged on the driving shaft to drive the feeding shafts, and means actuated by the gearing for raising and lowering the side-frames to carry the feeding disks into and out of contact with the bottom sheet of the stack.

5. In a paper-feeding apparatus, in combination, a support for a stack of paper sheets, driving mechanism and feeding disks below the support, means for raising and lowering the driving mechanism and disks to carry the latter into and out of contact with the bottom sheet of the stack, a train of gears arranged to rotate the feeding

disks and actuate the raising and lowering means, the driving mechanism constructed to drive the gear-train at a speed increasing from the minimum at the beginning of the contact of the disks with the paper to the maximum by the time the disks are withdrawn from contact.

6. In a paper-feeding apparatus, in combination, a support for a stack of paper sheets, a pair of vertically movable side-frames below the support, transverse feeding shafts journaled in the side-frames and carrying feeding disks, driving gears on the shafts, connecting gears meshing with the driving gears, and cams located at both ends of the side frames and actuated by the connecting gears for raising and lowering the side frames to carry the feeding disks into and out of contact with the paper.

20 7. In a paper-feeding apparatus, in combination, transverse feeding shafts carrying feeding disks; a gear-train arranged to rotate the shafts; a driving gear associated with the train to actuate the same; a driving shaft having a gear in mesh with the driving gear and having a crank provided with a crank-pin; and a power shaft adjacent to the driving shaft and having a slotted arm engaging the crank-pin to revolve the crank and its shaft.

25 8. In a paper-feeding apparatus, in combination, a support for a stack of paper sheets; feeding disks below the same; mechanism, including rotary cams, for raising and lowering the feeding disks to carry the

same into and out of contact with the bottom sheet of the stack; a driving gear; and a gear-train connected with the driving gear for rotating the cams and the feeding disks, constructed to rotate the cams at the same 40 rate as the driving gear and to rotate the feeding disks at a different rate.

9. In a paper-feeding apparatus, in combination, a support for a stack of paper sheets, transverse feeding shafts below the 45 support carrying feeding disks, a gear train arranged to rotate the shafts, a driving gear associated with said train to drive the same, and mechanism intermediate the driving shaft and the power shaft for driving the 50 former and to allow the axis of the driving shaft to move relative to the axis of the power shaft.

10. In a paper feeding apparatus, in combination, a support for a stack of paper 55 sheets, a pair of vertically movable side frames below the support, transverse feeding shafts journaled in the side-frames and carrying feeding disks, driving gears on the shafts, connecting gears meshing with the 60 driving gears, guides located at the ends of the side-frames, and means actuated by the connecting gears to raise and lower the side frames.

In testimony whereof I amx my signature 65
in the presence of two subscribing witnesses:
